UNITED STATES PATENT OFFICE

CHARLES H. ECKMANN, OF DETROIT, MICHIGAN

COIN-OPERATING DEVICE FOR VENDING MACHINES

Original application filed September 27, 1926, Serial No. 137,886. Divided and this application filed May 15, 1929. Serial No. 363,118.

This application is a division of my former application, Ser. No. 137,886, filed September 27, 1926, covering the coin operating mechanism as therein shown.

- 5 The object of my invention is to provide a coin operating device adapted to vending machines which will provide a means for collecting money in payment of merchandise without an attendant.
- 10 Another object is to provide a coin operating device that is provided with suitable locking mechanism and will prevent the vending machine to which it is attached from being operated except at times when a coin has 15 been previously inserted therein.

A further object is to produce a coin operating device for vending machines that is automatic and which will operate automatically when a coin is dropped therein and in a 20 manner for releasing the mechanism for one rotation only.

These several objects are attained in the preferred form by the construction and arrangement of parts more fully hereinafter set 25 forth.

Similar parts on all drawings are marked by similar numerals.

Fig. 1 represents the front side of my device, showing the coin operating levers and 30 means for connecting with the geared operating mechanism of a vending machine.

Fig. 2 is a side view of the device, showing the relative position of the operating members.

Fig. 3 is a sectional view taken on the line 3—3 of Fig. 2, showing the operating mechanism and the relative position of the operating parts.

The invention herein resides in the coin operating mechanism, the device being connected with the mechanism of the cigarette vending machine, as shown in the prior patent, of which this application is a division 45 thereof. The entire mechanism of both vending machine and the coin operating mechanism is fully described in the specifications to more clearly set forth the application of the coin operating mechanism.

50 I will now describe more fully the detailed

construction of my device, referring to the drawings and the marks thereon.

My device comprises a rectangular shaped metal frame of suitable proportions and design for supporting both the vending and coin operating mechanism. The vending machine is positioned at the top and a coin slot is provided in one side of the device which releases the locking mechanism, when a coin is dropped therein. In the top of the frame 55 is a supply roller for carrying a small roll of cigarettes, the cigarettes being attached to a strip of paper at uniform intervals, and rolled thereon in a manner that the end will engage the double corrugated feed rolls which 60 will rotate with the operating mechanism of the device, the same to be cut from the strip by an operating knife, cutting off one cigarette at each operation of the machine, and depositing the same in an open recess in 65 the front of the machine. The machine is so designed that it is locked at all times, except when a coin is resting in the coin slot, which allows one complete operation before depositing the coin in a box below, and again locking 70 the machine.

The frame —1— is preferably made of thin sheet metal side plates —2— and —3—, connected by the separator tubes —4— and firmly bolted together by the bolts —5— passing 75 therethrough, and forming a stiff, rigid frame. Near the top of the frame —1— is mounted a support roller —6—, rotatably mounted within the frame —1— by the shaft —7— which passes therethrough and 80 engages bearings in the side plates —2— and —3—. Directly beneath the support roller —6— are mounted two corrugated feed rolls —8— and —9—, also rotatably mounted in the frame —1— by the shafts —10— and —11— 85 which pass through the axis of the rollers and engage bearings in the side plates —2— and —3—. The said feed rollers —8— and —9— are placed close together and positioned parallel to the axis of the supply roller —6—, 90 and are formed with a series of corrugated grooves —12— thereon which roll together, and are of a size to receive a cigarette therein. The two rollers are connected by means of 95 gears —13— and —14— fixedly attached to 100

the ends of the shafts —10— and —11—, meshing together and causing both corrugated rolls to operate together, for passing a cigarette therethrough. The grooves —12— in each roll are positioned to meet and coincide with the grooves on the opposite roll. The cigarettes 63 are mounted on a narrow strip of paper —60—, spaced equidistant thereon and corresponding to the spacing of the corrugated grooves —12— of the feed rollers, and rolled on the supply roll —6—, but having the end of the roll engaged between the feed rollers —8— and —9—. Directly beneath the feed rollers —8— and —9— is mounted a knife —15—, made of a thin metal blade, and fixedly attached to the slide bars —16— and —17—. The slides —16— and —17— are slidably mounted in the cross bars —18— and —19— fixedly attached to the frame —1—, and sliding in a manner as to allow the knife —15— to move back sufficiently to allow a single cigarette to pass. A partition wall —20— is fixedly mounted in the frame —1—, positioned opposite the knife —15—, and is provided with a knife slot —21— for engaging the knife blade therein and for cutting a single cigarette from the roll as the corrugated feed rollers turn. A spring bar —22— is attached to the edge of the knife blade —15— and is supported in the cross bar —19—, but free to slide therein. A coil compression spring —23— is mounted on the said spring bar —22—, and in such a manner as to force the knife —15— into the slot —21— when the same is released. An operating handle —24— is pivotally mounted on the outside of the frame —1—, and is supported by the shaft —25— which passes through the side plates —2— and —3—. Fixedly mounted on the shaft —25— is an operating arm —26—, which carries a ratchet arm —27— pivoted to the outer end thereof. Said ratchet arm —27— engages a drive ratchet gear —28— fixedly attached to the end of the feed roller shaft —10—, and in such a manner that to rock the operating handle —24— on its supporting shaft —25—, it will cause rotation of both of the feed rollers —8— and —9—, sufficiently to pass only one groove —12— by the center of the roller, for each operation of the arm, thus deliver only one cigarette for each operation of the handle —24—, the ratchet gear —28— operating always in the same direction. On the opposite end of the shaft —10—, outside of the casing —1—, is fixedly attached a segment gear —29—, so designed with alternate teeth sections —30— and clearance spaces —31—. Directly beneath the shaft —10— is mounted the knife operating shaft —32—, positioned parallel to the shaft —10— and rotatably mounted in the sides —2— and —3— of the frame —1—. On the outer end of the shaft —32— is fixedly attached a pinion gear —33—, positioned to engage the teeth sections —30— of the seg-

ment gear —29—, and to mesh therewith, but free to turn back within the alternate clearance spaces —31—, as the gear —29— rotates. Fixedly attached to the same shaft —32— are two small rack gears —34— and —35—, both of which mesh with the rack sections —36— and —37— of the knife slides —16— and —17—, and so arranged that as the shaft —10— is rotated through operation of the handle —24—, the segment gear —29— will engage the teeth sections —30— with the pinion gear —33—, causing a partial rotation thereof, forcing the knife —15— back on the supporting slides, allowing a single cigarette to pass, then the pinion gear —33— releases as it reaches one of the clearance spaces —31— in the segment gear —29—. The coil spring —23— behind the knife —15— causes it to return and cut the cigarette from the roll, the cigarette dropping in the slide —38— leading to the opening at the front of the frame. The cigarette is then obtainable by the operator. At the lower part of the operating arm —26— is formed an extended lever arm —39— which moves directly with the operating handle —24—. The lever —39— is provided with an engaging pin —40— projecting from the lower end thereof. Near the bottom of the frame —1— is mounted a rocker shaft —41—, rotatably mounted in the sides —2— and —3— and carries a slotted arm —42— fixedly attached thereto, and so positioned that the slot —43— therein will engage the pin —40— of the arm —39— and cause the shaft —41— to rock as the operating handle —24— is turned. A guide bar —44— is fixedly attached to the outside of the side plate —2—, and is provided with a notch recess —45—, for engaging the pin —40—, and limiting the movement of the operating handle —24— and connected mechanism, allowing movement for one cigarette only. The coil spring —65— is attached to the arm —42—, causing the return of the operating handle when released. On the front edge of the frame —1— is mounted a coin chute —46—, arranged to receive a coin —50— therein, at the top end thereof, and drop to the lower end thereof. Within the lower end of the chute —46— is projected the end of the trip lever —47—, the same being pivotally mounted on the side plate —3— by the rivet —48—, the lever —47— being raised in the coin chute opening —61— by means of a coil spring —49— attached to the opposite end of the lever, the spring —49— being of sufficient strength to raise the lever —47— in the coin chute opening, when no coin is in the slide. The weight of the coin —50— is sufficient to force the end of the lever —47— down to the bottom of the chute. The opposite end of the lever —47— engages the end of the locking bar —51— which is pivoted to the side plate —3— by the rivet —52—. The lock bar —51—, being provided with a ratchet tooth

—53—, engages a small ratchet gear —54— which is fixedly attached to the end of the shaft —41—, for locking the entire mechanism of the device when no coin —50— rests 5 on the lever —47— in the coin chute, but will unlock as soon as a coin —50— is inserted in the chute. Pivottally attached to the side plate —3— of the frame —1—, and in front of the slot —55— at the lower end of the coin 10 slide —46—, is mounted a stop arm —56—, designed to prevent the coin —50— from passing out of the chute after forcing the lever —47— down. The stop arm —56— is held in place by the link —57— attached to the 15 lock arm —58— on the shaft —41—, and is held in that position until the operating arm —24— is turned, thus causing a rotation of shaft —41— and releasing the coin —50— from the coin chute —46—, the coin —50— 20 passing out of the slot —55— in the lower edge thereof and into a receiving drawer —59— below, allowing the lock bar —51— to again lock the machine until another coin is inserted therein, also providing for the 25 vending of only one cigarette at a single operation with each coin inserted.

While I have described my invention, as applied to vending cigarettes, it is apparent that the device is equally as well adapted to 30 use in vending other forms of merchandise as well, and can be applied to cigars as well as to cigarettes, or to any form of merchandise than can be placed in a roll.

Having fully described my coin operating 35 device for vending machines, what I claim as my invention and desire to secure by Letters Patent is:

1. A coin operating device used in combination with a vending machine adapted for 40 locking and regulating the use of the same, comprising a coin chute fixedly mounted in the vending machine frame, a gravity coin lever fixedly mounted within the said frame positioned to interpose one end of the said 45 coin lever within the said coin chute and turn on its supporting pivot under the weight of a coin, means mounted on the coin chute for retaining the coin on the gravity lever until the vending machine has been operated, 50 a ratchet locking wheel rotatably mounted within the said machine frame and connected to the vending machine operating mechanism, a locking bar pivotally mounted on said frame positioned to engage and lock the 55 said ratchet wheel and connected mechanism, said locking bar being connected to the pivoted gravity coin lever in a manner to disengage the ratchet locking wheel when the coin lever is tilted under a coin weight and 60 means attached to the gravity coin lever to return the same to its horizontal position and relock the vending machine.

2. A coin operating device used in combination with the vending machine for locking 65 and regulating the use thereof, comprising a

coin chute fixedly mounted within the vending machine, a gravity coin lever pivotally mounted within the said frame positioned to interpose one end of the said coin lever within the coin chute and turn upon its supporting pivot under coin weight interposed thereon through the coin chute, a ratchet locking wheel rotatably mounted within said frame and connected directly with the vending machine operating mechanism rotating therewith, a toothed locking bar also mounted within said frame positioned to engage the ratchet locking wheel and prevent rotation thereof thereby locking the vending machine mechanism, said locking bar being connected to the swinging end of the gravity coin lever in a manner to be disengaged from the locking ratchet wheel when said gravity lever is tilted by a coin weight, a spring attached to the gravity coin lever to return same to the initial locking position when the coin is released therefrom for re-locking the ratchet wheel and connected vending machine operating mechanism, and a coin stop arm pivotally mounted on said coin chute connected directly with the vending machine operating mechanism for retaining the coin weight on the gravity coin lever until after the machine is operated and then release the coin from the chute.

In witness whereof, I sign this specification.

CHARLES H. ECKMANN.
